Des. 232,477
Patented Aug. 20, 1974

232,477

PORCH LIGHT FOR MOTOR HOMES

Howard R. Moon, Fort Atkinson, Wis., assignor to Lake Center Switch Company, Winona, Minn., and Guy F. Atkinson Company, South San Francisco, Calif.

Filed Dec. 6, 1972, Ser. No. 312,772

Term of patent 14 years

Int. Cl. D26—06, 05

U.S. Cl. D48—32 R

FIG. 1

FIG. 2

FIG. 3

FIG. 4

FIG. 5

FIG. 1 is a view in perspective of a porch light for motor homes showing my new design;

FIG. 2 is a view in front elevation thereof;

FIG. 3 is a view in side elevation thereof, the side opposite that shown being a mirror image;

FIG. 4 is a view in top plan thereof; and

FIG. 5 is a view in bottom plan thereof.

The rear, not shown, is devoid of ornamentation.

I claim:

The ornamental design for a porch light for motor homes, substantially as shown and described.
